UNITED STATES PATENT OFFICE.

FRANK J. KROMENAKER AND GRANT M. KROMENAKER, OF CHICAGO, ILLINOIS.

ROOFING.

Application filed March 18, 1922. Serial No. 544,755.

To all whom it may concern:

Be it known that we, FRANK J. KROMENAKER and GRANT M. KROMENAKER, both citizens of the United States, and residing at 5 Chicago, county of Cook, and State of Illinois, have invented certain new and useful Improvements in Roofing, of which the following is a specification.

This invention relates to a roofing composed of interlocking shingles, and is particularly concerned with the construction of the individual shingles by which they may be economically produced and be effectively combined to provide a rain-proof roofing. 10 An exemplification of this invention is shown in the accompanying drawings wherein—

Figure 1 is a plan view of a section of roofing composed of a number of the present shingles;

Figs. 2 and 3 are transverse and longitudinal sections therethrough taken respectively on lines 2—2 and 3—3 of Fig. 1;

Fig. 4 is a fragmentary view in plan of a sheet from which the shingles are cut; and

Fig. 5 is a plan view of one of the shingles per se.

The shingle unit shown in Fig. 5 is formed with opposite ends each of three sections 5, 6, and 7, the first and last being right angularly related to the upper and lower edges 8 and 9 respectively. The intermediate end sections 6 are obliquely inclined at angles of about 135° to the adjacent sections 5 and 7, being disposed in substantially right angular relation to each other. From this construction it follows that the oblique sections 6 diverge in an upward direction, and that the dimension 35 of the upper edge 8 is considerably greater than that of the lower edge 9. Additionally, in the body of the shingle are formed two cuts or slits 10 each aligned with an oblique section 6 and proceeding inwardly therefrom for a distance which is perhaps half way toward the lower edge 9.

Shingles of the form described may be produced without waste of material from a standard sheet of roofing, such, for instance, as is shown in Fig. 4, wherein it appears that the width of such a sheet may be approximately twice the vertical dimension of a single shingle. The relationship of the several shingles prior to their being cut from the sheet may best be understood by referring to the markings in Fig. 4

which define shingles designated as A, B, C, D, E and F. The shingles A, B and C lie in one course to one side of a center line 11 which runs longitudinally of the sheet, while the shingles D, E and F are arranged in another course that lies to the opposite side thereof. The several shingles in each course are alternately inverted throughout the length of the sheet, being 65 contiguous to each other along the lines 5, 6, and 7; these are also the lines of severance, becoming subsequently the end sections 5, 6 and 7 shown in Fig. 5. The shingles so marked in one course preferably 70 lie opposite other shingles in inverted relation in the adjacent course, and from this arrangement it results that the end sections 5 of two adjacent shingles in opposite courses are brought into alignment. This 75 is the preferred relationship, as thereby the operation of severance is facilitated.

In utilizing shingles of such a construction to provide a water-tight roofing, we combine the same as follows: Upon a roof, 80 usually slanted, the shingles are arranged in horizontal rows, as indicated in Fig. 1, with the end sections 5 in abutting relation. The top row comprises shingles designated as a, b, and c, the next lower row includes 85 other shingles d and e, while in the row next in order are shingles f, g and h. These rows are in practice first formed at the lower edge of the roof, but for convenience in description, we will consider mainly 90 those along its upper edge. Below the topmost shingle row, each succeeding row is lower by a distance about equal to the length of the end sections 5 or 7, these being of the same dimension. In the second row, 95 however, the shingles are staggered with respect to those in the top row in that the abutting edges of the second row shingles lie about midway of the horizontal length of those in the top row. The shingles in 100 the third row align with those in the top row and hence are staggered with respect to those in the second row, and this staggered arrangement is followed through to the bottom shingle row.

It will be apparent that each row of shingles laps partly over the next lower row and also the row therebelow, as indicated in Fig. 2. Portions of each shingle so overlapped do, however, overlap the adjacent lower corners of the proximate shingles in 110 the next higher row. This is accomplished

by passing edge portions of the under shingles through the slits 10 in the upper shingles, as shown in Fig. 1. From this arrangement it results that each shingle is interlocked with those contiguous thereto, to provide a roofing which is both firm and secure. In laying the roofing, nails may be used to fasten the shingles to the roof in the manner now customary, the preferred place of fastening being adjacent the end sections 5 as indicated by the numerals 12 in Fig. 1.

The roofing formed by our invention presents an appearance that is both attractive and unusual. The portion of each shingle exposed to view is bordered by straight lines at top and bottom, and at each end by three-part zigzag lines which coincide with the zigzag borders of the adjacent shingles. The exact dimensions and angular relationship of the shingle edges are, of course, variable within certain limits, but those suggested in the drawings are well suited to the purposes of this invention for which protection is hereby sought in claims as follows:

We claim:

1. As a new article of manufacture, a roofing shingle having a lower edge, ends which extend upwardly in right angular relation thereto, thence outwardly in diverging relation, and thence upwardly again in parallelism with the first mentioned sections thereof, and a top edge parallel to the lower edge; there being slits extending into the body of the shingle in line with the outwardly extended end sections, substantially as described.

2. As a new article of manufacture, a roofing shingle having diverging edges in substantially right angular relation with each other, there being parallel continuations at each extremity thereof forming an angle of approximately 135° therewith, and upper and lower edges in parallelism, there being slits extending into the shingle body in line with the diverging edges, substantially as described.

3. A roofing comprising, in combination, a plurality of shingles each having upper and lower edges of unequal length, ends consisting of two parallel sections and an intermediate oblique section which is angularly related to the other corresponding section, the several shingles so formed being arranged in rows with one parallel end of each in abutting relation to the corresponding end of the other, and each succeeding lower row of shingles occupying a staggered end-wise relation to the one above, each row of shingles being overlapped in part by the row above, there being slits in alignment with

the oblique ends of each shingle extending into the body thereof permitting the underlapping shingle in the next lower row to pass therethrough to the upper side thereof to overlap a portion of the upper shingle, substantially as described.

4. A roofing comprising, in combination, a plurality of shingles each having upper and lower edges in parallelism and ends therebetween which provide three sections the intermediate ones of which are obliquely related to each other at an angle of about 90°, the several shingles so formed being arranged in a row with one of their end sections in abutting relation with a corresponding section of the other, other rows of shingles similarly arranged and each disposed parallel to the first row and each arranged to partially overlap the one therebelow, there being slits formed in each shingle through which a portion of the overlapped shingle may extend to lie upon the outer side thereof, substantially as described.

5. A roofing comprising, in combination, a plurality of shingles, all alike, and each slotted to interlock with those adjacent by lapping a portion of itself therebelow and a portion thereabove, the several shingles being formed with parallel upper and lower edges of unequal length and with side edges having three sections the end ones of which are in right angular relation to the upper and lower shingle edges, the middle sections being obliquely related thereto, the assembly of shingles so formed providing a roofing with exposed shingle surfaces bordered by upper and lower edges in parallelism and zigzag ends in three sections one of which is co-incident with the corresponding sections of the proximate shingles, substantially as described.

6. A roofing comprising, in combination, a plurality of shingles, all alike, and each slotted to interlock with those adjacent by lapping a portion of itself therebelow and a portion thereabove, the several shingles being formed with parallel upper and lower edges of unequal length and with side edges having three sections the end ones of which are in right angular relation to the upper and lower shingle edges, the middle sections being obliquely related thereto, the assembly of shingles so formed providing a roofing with exposed shingle surfaces which have two opposite edges in parallelism and the remaining edges of zigzag formation, substantially as described.
